WHIRLING TOY

Jacob M. Field, Brooklyn, N. Y.

Application June 13, 1950, Serial No. 167,717

2 Claims. (Cl. 46-61)

1

This invention is an attractive and easily operable toy adapted to be bodily rotated about its own axis on the release of a coiled string and adapted to continue its rotation pursuant to complete unwinding of this string to automatically rewind the latter and thereafter further continue rotation upon successive unwinding and winding phases of this string. Specifically one object of the invention resides in the utilization of spaced hollow discs interconnected by nested means constituting a hollow drum about which the free part of the string is initially and manually coiled or wound up. More particularly another object is realized in the provision of spaced hollow casings including transparent covers to permit viewing of spinning members rotatable within the casing each of which embody laterally extending collars adapted to be telescoped and secured together for holding the casings a predetermined distance apart to define an annular channel in which the string is adapted to be coiled about a drum characterized by the nested or telescoped collars having registering or aligned gaps for receiving a part of the string and specifically also constituting keeper means in which the knotted end of the string is effectively retained. The invention aims further to improve generally and enhance the utility of spinning toys hereinafter specifically described and shown in the accompanying drawings wherein:

Fig. 1 is a perspective view of the whirling toy according to my invention.

Fig. 2 is a front elevational view of Fig. 1.

Fig. 3 is a horizontal transverse sectional view on the line 3—3 of Fig. 2.

Figs. 4 and 5 are fragmentary inside elevational views of the complementary keeper means for retaining the inner knotted end of the string within the toy.

Fig. 6 is a perspective and exploded view of Fig. 1, and

Fig. 7 is a fragmentary view of Fig. 6 however illustrating the companion housings.

The toy broadly denoted T according to the invention is characterized by the spaced hollow discs DA and DB each constituting a closed housing each defined by a casing CA and a complementary transparent cover C.

More specifically, each casing embodies a circular wall CW including a circumferential rim R.

Each wall CW also includes an inside boss B from each of which projects a stub shaft S arranged concentrically within and cast integral

2

with its respective wall CW. However shaft S projects appreciably beyond respective rims R.

Extending outwardly from wall CW of hollow disc DA is the annular collar 10 interrupted by gap 11.

Neck or collar 12 projects outwardly from wall CW of hollow disc DB and is also characterized by a gap or slot 13.

Closures or covers C of discs DA and DB are identical and each is characterized by an outside wall 14 and the inside concavity 15. Each of these covers is also appropriately rabbeted to form the annular flange 16 and the companion annular stop shoulder 17.

Complementary members such as casing CA and its cover C are preferably cast from an appropriate plastic material and when assembled define an internal chamber 20 in which a suitable cardboard diaphragm 21 is arranged for free rotation on stub shafts S. Each of these diaphragms embodies an opening 22 to receive its shaft S and is arranged in a respective casing as CA before being covered by its closure or cap C. To stimulate interest, each diaphragm 21 carries a caricature and as illustrated the picture of a clown. As seen in the drawing, the diaphragm 21 is substantially larger than the boss B, and the peripheral edge of the diaphragm or design member 21 extends beyond the peripheral edge of the boss B. Thus, when the diaphragm 21 rotates, a substantial portion of it is free from frictional contact with the wall CW and the boss B.

After mounting the diaphragm in a casing, a cover C is attached thereto by positioning annular flange 16 into rim R and these parts in fact are force fitted and also secured by a plastic cement to prevent separation, thus forming a hollow disc such as DB.

The enlarged or knotted end K of cord or string 30 is positioned into neck 12 with the string arranged in gap or slot 13. Thereafter casing CA of disc DB has its collar 10 arranged to receive neck 12 of disc DB and the string is arranged in the slot or groove 11. These collars therefore are in close nested relation and are fastened or glued together by appropriate plastic cement thus constituting a hollow cylindrical drum about which the string may be wound and at the same time holding discs DA and DB a predetermined distance apart.

Gaps 11 and 13 of course are in registration and the collars 10 and 12 may be considered as telescoped means permitting coupling a pair of hollow discs although in spaced relation to form

the annular channel 31 in which the anchored string is wound. Also collars 10 and 12 are hollow keeper means for retaining the knotted end of the string.

By winding string 30 about the drum and thereafter allowing the herein toy in the form of coupled hollow discs to drop by gravity the string is unwound. Automatically thereafter the toy winds up the string. During such actions the diaphragms 21 within the hollow discs DA and DB rotate relative to the latter about their respective stub shafts S, giving the impression that the clowns are going through acrobatic effects which action may be observed through the plastic transparent closures or covers C nested within their respective casing.

In the assembled relation of the hollow discs, the shafts S thereof are disposed contiguous to the covers C to preclude the rotatable cards or diaphragms 21 from falling off. It follows that as the hollow discs bodily rotate together, diaphragms 21 are rotating on their respective shafts S between their covers C and bosses B.

Various changes may be made in details of construction and arrangement of parts without departing from the spirit of the invention or sacrificing any of the advantages thereof inherent therein.

I claim:

1. In a spinning toy, a pair of discs, neck means extending from one face of one disc to one face of the other disc connecting said discs, a string connected at one end to said neck means, a boss extending from the other face of at least one of said discs, a stub shaft projecting from said boss, said stub shaft having a free end, a peripheral annular rim extending from said other face, a transparent cover, an annular flange on said transparent cover, said annular flange and said peripheral annular rim being telescopingly nested one within the other, whereby said transparent

cover is secured to said disc, a design member mounted on said stub shaft for free rotation thereon, the outer periphery of said design member extending substantially beyond the outer periphery of said boss, a portion of said transparent cover being closely adjacent the free end of said stub shaft to retain said design member on said stub shaft between said boss and said cover.

2. In a spinning toy, a pair of discs, neck means extending from one face of one disc to one face of the other disc connecting said discs, a string connected at one end to said neck means, a stub shaft extending from the other face of at least one of said discs, said stub shaft having a free end, a peripheral annular rim extending from said other face, a transparent cover, an annular flange on said transparent cover, said annular flange and said peripheral annular rim being telescopingly nested one within the other, whereby said transparent cover is secured to said disc, a design member mounted on said stub shaft for free rotation thereon, a portion of said transparent cover being closely adjacent the free end of said stub shaft to retain said design member on said stub shaft between said other face and said cover.
